US0D1105068S

(12) **United States Design Patent** (10) **Patent No.:** **US D1,105,068 S**
(45) **Date of Patent:** **** Dec. 9, 2025**

(54) **PROTECTIVE CASE FOR SMART WATCH**

(71) Applicant: **Shenzhen Kaisennick Intelligent Technology Co., Ltd.**, Shenzhen (CN)

(72) Inventor: **Yongkai Zhou**, Shenzhen (CN)

(73) Assignee: **Shenzhen Kaisennick Intelligent Technology Co., Ltd.**, Shenzhen (CN)

(**) Term: **15 Years**

(21) Appl. No.: **29/951,782**

(22) Filed: **Jul. 11, 2024**

(30) **Foreign Application Priority Data**

Jul. 2, 2024 (CN) 202430411567.2

(57) **CLAIM**

The ornamental design for a protective case for smart watch, as shown and described.

DESCRIPTION

FIG. 1 is a front, left and bottom perspective view of a protective case for smart watch, showing my new design; FIG. 2 is a rear, right and top perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the protective case for smart watch that form no part of the claimed design.

1 Claim, 8 Drawing Sheets
